PISTON

Adolph L. Nelson, Detroit, Mich.

Application May 28, 1935, Serial No. 23,808

11 Claims. (Cl. 309—10)

This invention relates to pistons, especially to pistons for use in internal combustion engines.

A particular object of the invention is to provide balancing ribs on the lower inner wall of the skirt that are divided into tooth-like segments so as to reduce or avoid any stiffening of the skirt.

These and other objects and advantages of the invention will become apparent as the description proceeds.

While a preferred form of the invention has been disclosed herein for purposes of illustration, various changes may be made in the construction without departing from the spirit of the invention as hereinafter set forth and claimed.

In the drawings:

Fig. 1 is a side elevation of a piston embodying the invention;

Fig. 2 is a plan view of the lower end of the piston looking toward the head;

Fig. 3 is a sectional view on line 3—3 of Fig. 1;

Fig. 4 is a sectional view on line 4—4 of Fig. 3;

Fig. 5 is a view similar to Fig. 4, of a modification;

Fig. 6 is a sectional view on line 6—6 of Fig. 5;

Fig. 7 is a view similar to Fig. 4, but showing a modification;

Figs. 8 and 9 are views similar to Figs. 4 and 2 of a further modification.

The piston illustrated in the drawings is in general the type of piston described in my Patent No. 1,982,396. This piston includes piston pin bosses 10, opposite thrust faces 11, 12, and an annular part 13 below the pin bosses, which is reinforced by arcuate segmental ribs 14 covered by my Patent No. 1,830,172. The present invention relates particularly to the toothed ribs 15 located between the piston pin bosses and the ribs 14.

Each rib 15 extends along the inner surface 40 of the annular part 13 below a pin boss, and the ends of these ribs are spaced from each other behind the thrust faces in order to permit casting the piston in a permanent mold with a three-piece core, as fully explained in Patent No.

45 1,830,172. For this purpose the inner skirt wall in the vertical zone in the center of each thrust face is free of any inwardly extending ribs or projections over a considerable arc, as will be clear from Figs. 2 and 3.

50 Each of the ribs 15 is cut through by one or more slots 16 which divide the rib into a plurality of separate, segmental portions. The slots 16 cut practically through the entire thickness of the rib so that outside of each slot the skirt 55 wall has substantially its normal thickness, thus

permitting the skirt to bend circumferentially at these points as freely as though the ribs 15 were not present. This free yielding of the ribs 15 is of particular importance in a strut-controlled piston of the type illustrated, as the struts tie rigidly together the parts of the skirt to which they are attached. It is obvious that the depth of the slots can be varied to alter the stiffness of the ribs.

The slots 16 are substantially parallel to the 10 axis of the piston pin bosses, as illustrated, so as to permit casting the piston with a three-piece core. This arrangement of the slots permits moving the side cores toward the center of the piston in directions parallel to the axis of the pin 15 bosses.

The ribs 15 are for the purpose of providing surplus material that can be machined away to bring the piston to a certain weight in order to balance it with others of a set. This is usually 20 done by machining away part of the inner periphery of the ribs. The division of the ribs into separate tooth-like portions prevents distortion of the piston due to casting strains, as would result if the ribs were solid. This is of great importance 25 because the piston cannot be balanced for weight until after it has been given a preliminary finishing on the outside. Generally the piston is first machined to an oversize, leaving say 10 grams of material to be removed in the final 30 machining. Then if the final weight of the finished piston is to be 350 grams, metal is removed from the balancing ribs until the piston weighs 360 grams. The piston is last given the finish 35 grinding which removes the extra 10 grams from the exterior surface. If the balancing ribs were cast solid, the act of cutting away part of these ribs to balance the piston weakens the ribs and releases certain casting strains that were held 40 in check by the relatively stiff ribs during the preliminary machining of the piston, thus throwing the skirt out of round, twisting the pin bosses out of line, putting the ring grooves out of true, etc.

Another advantage of this construction is that 45 the skirt remains of practically the same stiffness regardless of the amount of material removed from the ribs in balancing the piston. If the ribs were cast solid there would be a great difference in the skirt stiffness, ranging from the 50 full stiffening effect when the rib is left intact to the entire absence of the stiffening effect of the rib if the rib is entirely cut away.

The toothed balancing ribs 15 can be used on any desired type of piston, and they can be lo- 55

cated at any suitable position on the inside of the skirt. Figs. 5 and 6 show a modification in which the ribs 15 are located on the inner walls of the thrust faces in the horizontal zone of the piston 5 pin bosses.

The reinforcing ribs 14 may be dispensed with, or they may be placed above the toothed ribs, as shown in Fig. 7, which illustrates the application of the ribs to a piston of the all-aluminum trunk 10 type.

In some forms of the invention the reinforcing ribs 14 may be attached to the toothed ribs 15, as shown in Figs. 8 and 9. In this case as much as necessary of the toothed balancing ribs 15 can 15 be machined out, but the machining is never permitted to cut into the ribs 14. Thus the ribs 14 always provide definite minimum stiffness in the skirt even after all of the balancing ribs 15 have been cut away.

20 The present application is in part a continuation of my co-pending application Serial No. 631,968, filed September 7, 1932.

I claim:

1. A piston comprising a head, a skirt connected to the head, a balancing rib extending inwardly from the wall of the skirt, the balancing rib being formed with at least one slot extending toward the outer wall of the piston and dividing the rib into a plurality of separate portions the said rib furnishing excess material and being designed to be cut away to balance the piston with others of a set without substantially altering the strength or stiffness of the skirt.

2. A piston comprising a head, a skirt connected to the head, a balancing rib extending inwardly from the wall of the skirt, the balancing rib being formed with a plurality of slots extending toward the outer wall of the piston and dividing the rib into a plurality of separate portions the said rib furnishing excess material and being designed to be cut away to balance the piston with others of a set without substantially altering the strength or stiffness of the skirt.

3. A piston comprising a head, a skirt connected to the head, a pair of arc-shaped ribs extending inwardly at the lower part of the skirt, and located below the pin bosses, each rib being formed with at least one slot extending toward the outer wall of the piston and dividing the rib 50 into a plurality of separate portions the said ribs furnishing excess material, and being designed to be cut away to balance the piston with others of a set without substantially altering the strength or stiffness of the skirt.

4. A piston comprising a head, a skirt connected to the head, a pair of arc-shaped ribs extending inwardly at the lower part of the skirt, and located below the pin bosses, each rib being formed with a plurality of slots extending toward the outer wall of the piston and dividing the rib 60 into a plurality of separate, tooth-like portions the said ribs furnishing excess material, and being designed to be cut away to balance the piston with others of a set without substantially altering the strength or stiffness of the skirt.

5. A piston comprising a head, a skirt connected to the head and having a lower circular portion, piston pin bosses, partly-cylindrical portions extending upwardly from the circular portion, a pair of arc-shaped balancing ribs, each of the balancing ribs extending along the inner surface of the lower circular portion below a pin boss, the balancing ribs being spaced from each 70 other at the inner surface of each of the partly-

cylindrical portions, each balancing rib being formed with at least one slot extending toward the outer wall of the piston and dividing the rib into a plurality of separate portions the said ribs furnishing excess material, and being designed to be cut away to balance the piston with others of a set without substantially altering the strength or stiffness of the skirt. 5

6. A piston comprising a head, a skirt connected to the head and having a lower circular portion, piston pin bosses, partly-cylindrical portions extending upwardly from the circular portion, a pair of arc-shaped balancing ribs, each of the balancing ribs extending along the inner surface of the lower circular portion below a pin 10 boss, the balancing ribs being spaced from each other at the inner surface of each of the partly-cylindrical portions, each balancing rib being formed with a plurality of slots extending toward the outer wall of the piston and dividing the rib 15 into a plurality of separate, tooth-like portions the said ribs furnishing excess material, and being designed to be cut away to balance the piston with others of a set without substantially altering the 20 strength or stiffness of the skirt. 25

7. A piston comprising a head, a skirt connected to the head, piston pin bosses, a pair of arc-shaped balancing ribs extending inwardly at the lower part of the skirt, each balancing rib being formed with a plurality of slots extending toward the outer wall of the piston and dividing the rib 30 into a plurality of separate, tooth-like portions, the slots being arranged in opposed pairs, the slots of each pair opening inwardly toward each other in a direction substantially parallel to the axis of the pin bosses to permit molding the piston with a three-piece core, the said ribs furnishing excess material and being designed to be cut away to balance the piston with others of a set without substantially altering the 35 strength or stiffness of the skirt. 40

8. A piston comprising a head, a skirt connected to the head and having a lower circular portion, piston pin bosses, partly-cylindrical portions extending upwardly from the circular portion, a pair of arc-shaped balancing ribs, each of the balancing ribs extending along the inner surface of the lower circular portion below a pin boss, the balancing ribs being spaced from each other at the inner surface of each of the partly-cylindrical portions, each balancing rib being formed with a plurality of slots extending toward the outer wall of the piston and dividing the rib 45 into a plurality of separate, tooth-like portions, the slots being arranged in opposed pairs, the slots of each pair opening inwardly toward each other in a direction substantially parallel to the axis of the pin bosses to permit molding the piston with a three-piece core, the said ribs furnishing excess material and being designed to be cut away to balance the piston with others of a set without substantially altering the 50 strength or stiffness of the skirt. 55

9. A piston comprising a head, a skirt connected to the head having opposite thrust faces and a lower circular portion, piston pin bosses, a pair of arc-shaped balancing ribs, each of the balancing ribs being located below a pin boss and extending along the inner surface of the lower circular portion, the balancing ribs being spaced from each other at the inner surface of each thrust face, the inner wall in the vertical zone in the center of each thrust face being free of any inwardly extending projections over a considerable arc, each balancing rib being formed with 60 70 75

a plurality of slots extending transversely of the rib and dividing the rib into a plurality of tooth-like portions the slots being arranged in opposed pairs, the slots of each pair opening inwardly toward each other in a direction substantially parallel to the axis of the pin bosses to permit molding the piston with a three-piece core, the said ribs furnishing excess material and being designed to be cut away to balance the piston with others of a set without substantially altering the strength or stiffness of the skirt.

10. A piston comprising a head, a skirt connected to the head and having opposite thrust faces and a lower circular portion, piston pin bosses, a pair of arcuate reinforcing ribs extending inwardly from the skirt wall, and a pair of arcuate balancing ribs, each balancing rib being divided by slots into a plurality of separate tooth-like portions, said balancing ribs furnish-

ing excess material, and being designed to be cut away to balance the piston with others of a set without substantially altering the strength or stiffness of the skirt.

11. A piston comprising a head, a skirt connected to the head and having opposite thrust faces and a lower circular portion, piston pin bosses, a pair of arcuate reinforcing ribs extending inwardly from the skirt wall, each of said reinforcing ribs being located with its intermediate 10 portion below the opening of a piston pin boss, and an arcuate balancing rib located below each reinforcing rib, said balancing ribs being slotted into a plurality of separate tooth-like portions and furnishing excess material and being designed 15 to be cut away to balance the piston with others of a set without substantially altering the strength or stiffness of the skirt.

ADOLPH L. NELSON.
